TAKE-UP REEL FOR KNITTING MACHINES AND METHOD OF OPERATION

Frederick W. Ruehling, Philadelphia, and Herbert Erich Haehnel, West Reading, Pa., assignors to Textile Machine Works, Wyomissing, Pa., a corporation of Pennsylvania

Application February 14, 1948, Serial No. 8,334

20 Claims.

(Cl. 66—149)

1
This invention relates to fabric draw-off reel units for full-fashioned and other flat knitting machines and more particularly to draw-off reel units permitting the quick removal of fabric from the unit with a minimum of pull on the fabric and to a method of operating a knitting machine equipped with such a reel unit.

As is well known, many of the present full-fashioned knitting machines are used principally for knitting flat blanks, including the leg and foot portions, for full-fashioned hosiery. These machines are provided with fabric draw-off reel units, one for each of the several knitting sections of the machine and which are connected to the folded welt portion of the blanks by means of straps having their free ends connected to welt wires which extend in normal manner through the turned welts. As the fabric is knitted after the welt has been turned, said straps are wound on the reel units for their full lengths and then considerable portions of the stocking blanks are wound on the reel units. When the blanks have been completed and with the last courses of each blank on the needles, the machine is stopped and the tension on the reel shaft is released. The welt wires are removed from the welts and the blanks pressed-off the needles in the usual manner, after which the blanks are stripped off the reel units. In the majority of instances, the blanks freely slip on the reel surfaces and are removed quickly and without damage. However, at times a blank catches in some way and considerable tugging is necessary to remove it from the reel and any unusual tension will cause damage to the blank.

It is an object of the present invention to provide a reel unit structure adapted to avoid damage to the blanks during their removal from the unit.

Another object of the invention is to provide a reel unit structure having a central section long enough to accommodate substantially the entire width of the blank and entirely free to rotate relatively to the reel shaft while the blank is being unwound or removed from the reel unit.

A further object of the invention is to provide means individual to each of the several reel units of a full-fashioned knitting machine which permits the locking of the free center portion of any reel unit to its mounting shaft.

Still another object is to provide a means ensuring removal of the blanks from the reel units with a minimum of pull on the blanks while permitting the units to be used in rigid condition throughout when desired.

2

With these and other objects in view, which will become apparent from the following detailed description of the form of the invention shown in the accompanying drawings, the invention resides in the novel method, elements, features of construction and arrangement of parts in cooperative relationship as hereinafter more particularly pointed out in the claims.

In the drawings:

10 Fig. 1 is a plan view of a fragment of a multisection full-fashioned knitting machine including only a single knitting section;

15 Fig. 2 is a sectional elevation taken substantially on the line 2—2 of Fig. 1, looking in the direction of the arrows, and in part broken away to show a feature behind the line of section.

Fig. 3 is a plan view on an enlarged scale, of the main reel unit shown in Figs. 1 and 2;

20 Fig. 4 is a sectional elevation taken substantially on the line 4—4 of Fig. 3, looking in the direction of the arrows, and enlarged relative to Fig. 3, the central portion of the unit being broken out;

25 Fig. 5 is a fragmentary view of the right hand end of Fig. 3 drawn to the same scale as Fig. 4, parts being broken away and parts being shown in section for purposes of illustration;

Fig. 6 is a sectional view taken substantially on the line 6—6 of Fig. 5, looking in the direction of the arrows;

30 Fig. 7 is a view similar to Fig. 5 except that certain parts are shown in different positions; and

Fig. 8 is a section taken substantially on the line 8—8 of Fig. 7, looking in the direction of the arrows.

In the drawings and description, only the means necessary to a complete understanding of the invention are specifically set forth; further information as to the construction and operation of other related, usual and well-known knitting machine elements, mechanisms, etc., may be found in one or more of the following publications:

45 1. Pamphlet entitled—Full-Fashioned Knitting Machines—published and copyrighted by the Textile Machine Works, Reading, Pennsylvania, in 1920.

50 2. Four catalogs entitled—The "Reading" Full-Fashioned Knitting Machine Parts Catalog—published and copyrighted by the Textile Machine Works, in 1929, 1935, 1940 and 1947, respectively.

55 3. Booklet entitled—The "Reading" High Production Full-Fashioned Knitting Machine—

which, forming a supplement to the above noted 1940 parts catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

It will be understood that the great majority of full-fashioned stockings now made have two 10 ply or turned welts, the blanks for such stockings having their first courses engaged by the hooks of welt bars forming a part of the well known automatic welt turning mechanism. After a predetermined amount of fabric has been knitted under tension applied to the welt bar, welt 15 rods or wires are placed on the blanks and the fabrics folded around the welt wires. As the fabrics are folded around the welt wires, draw-off tension is applied to the welt wires by means 20 of straps connected to fabric reels. At completion of the welt fabric the first and last courses of the welts are interknitted with subsequent courses to thereby close the welts. The major portions of the blanks are then knitted, the welt wires and parts of the blanks being wound up together on reels. At completion of the blanks and with the last course of loops of said blanks either remaining on the needles, or pressed therefrom as shown in the drawings, the tension is released from the reels and the welt wires removed from the straps and fabrics. After removing the welt wires the blanks are removed from the reels, this operation being customarily done by pulling upon the pressed-off end to unwrap the blanks from their respective reels.

In Figs. 1 and 2 of the drawings, the invention is shown applied to one section of a multi-section knitting machine having a welt turner of the type shown and described in the patent to Bitzer, No. 2,413,601, December 31, 1946, and shown in the hereinbefore referred to "Reading" parts catalog of 1947. The knitting section shown comprises loop forming means including a needle bar 10 having a row of needles 11 therein, sinkers 12, dividers 13 and a combined hook-up and welt turner means comprising a welt bar 15 having welt hooks 16 thereon. Bar 15 is slidably mounted on rails or bridge members 17 to move toward and away from the needle row and, when the loops of the first course of a blank are to be hooked up, the bar 15 is pushed along rails 17 until the hooks 16 extend between the needles. Bar 15 is shown in Fig. 1 in its rest or inactive position, the one farthest from the needles. For pushing the bar to the position for hooking up loops, the welt turner means is shown as having pins 20 also slidably on, as well as guided on, the rails 17 and normally in contact with resilient projections on the forward edge of bar 15. Linkages connect pins 20 with an oscillatable shaft 21 whereby pins 20 are pushed toward and withdrawn from the needle row at the desired times. After yarn for the first course of a stocking blank 22 has been laid by yarn carriers (not shown) and formed into loops around the needles by the sinkers 12 and dividers 13, the loops are engaged by the welt hooks 16 when the pins 20 are withdrawn from the needle rows. Alternate loops of the first course are cast off the needles by known means and in a known way, and knitting of the welt of the blank is proceeded with, draw-off tension being supplied to the loops through the welt bar 15 by an auxiliary draw-off shaft 23. The welt bar 15 is connected to the shaft by a strap 25, one end of which is attached to the welt

bar and the other end of which is attached to a reel 26 fixed to the shaft 23.

After a certain amount of welt fabric has been knitted, draw-off tension from a main draw-off means is substituted for that supplied by shaft 23. Preliminary to substituting the main draw-off shaft for the auxiliary draw-off shaft 23, pins 20 are pushed part way toward the needle row 11. As a further preliminary to so substituting the draw-off action of the main draw-off means for that of shaft 23, draw-off hooks 27, one of which is attached to each draw-off strap 30 of the main draw-off means, are moved, while under tension, toward the needle row by means of belts 31 which are operated by a shaft 32, means (not shown) latching the shaft 32 to hold the hooks stationary for purposes hereinafter set forth.

When a sufficient length of welt fabric is knitted, a welt wire 33 is placed on the fabric and inserted in slots in the facing sides of the rails 17 in position to be engaged by the hooks 27 on the straps 30. At a predetermined point in the formation of the welt, pins 20 move the welt bar 15 toward the needle row to a position intermediate the inactive position of the bar and the needle row and the bar is latched in said intermediate position. As the pins 20 move toward the needle row to push the bar 15 to said intermediate position, the belts 31 are unlatched and moved by means (not shown) to release the draw-off hooks 27 which then are drawn forward and catch the welt wire, causing it to fold the fabric below the welt bar and to draw the loops 35 of the first course forward on hooks 16 against elements 35 on the hooks to hold the loops in a position which facilitates returning them to the needles. After a further portion of welt fabric has been knitted, pins 20 are pushed toward the 40 needles to a position in which the welt is closed by transferring the loops of the first course back to the needles and interknitting the first and last courses of the welt.

In the form of the invention shown in the drawings the straps 30 are attached to a reel unit 36, one of which is provided for each knitting section, carried on a shaft 34 and forming part of the main draw-off means of the machine. The reel unit, shown in detail in Figs. 3 to 8 of the drawings, includes three cylindrical reel sections, two end sections 37 and 38 respectively and a central section 39 between sections 37 and 38 and in substantially abutting relationship thereto to define joints therebetween. Each of the end sections 37 and 38 comprises a shell-like member 41 carried on an outer bearing member 42 and an inner bearing member 43 fixed to shaft 34 by means of set screws 45, as shown in Fig. 4. The shell-like members 41 are held in fixed relation 50 to the bearing members 42 and 43 by pins 46, shown in Fig. 5. The center reel section 39 comprises a shell-like member 47 extended to overlie the joints between the sections and carried at each end on bearings 50 rotatably mounted on the shaft 34. The member 47 is held in fixed relation to its bearings 50 by means of pins 51, one of which is shown in Fig. 5. The center section 39 has a continuous and uninterrupted outer cylindrical surface so that there is nothing to impede the blanks from being pulled off the section 39, this ordinarily being done in the direction in which the blanks are wound thereon in knitting. Each end section 37 and 38 has a draw-off strap 55 attached thereto by the usual means which 60 comprises a pair of crossed slots 44 and 44A, re-

spectively, and a T-shaped anchor member 40, the outer ends of the straps having hooks 27 fixed thereto for use in connecting the straps to the welt wire 33 as hereinbefore set forth.

As shown in Fig. 1, the stocking blank is wound entirely on the center section 39 of the reel unit 36 although the widest part of the blank, which is the welt portion, is considerably wider, when knitted, than the center section 39, so that the edges of the blank form right and left hand helices. Fig. 1 also shows the blank pressed-off the needles and the reel shaft positioned with the welt wire 33 at the top of the reel unit 36. The welt wire is removed from the hooks 27 and the welt portion of the blank 22. The blank 22 is then removed from the section 39 with the section 39 rotating to permit the free unwinding of the blank.

In the knitting of stocking blanks such as 22, for one reason or another, an occasional blank is accidentally pressed from the needles before the blank is completed. In this case, the needle bar of the pressed-off knitting section is laid out of operation while the remainder of the blanks are completed. The pressed-off blank is placed on a topping bar and prior to the start of the next or a subsequent set of blanks is topped back on the needles from which it was originally pressed. When knitting has reached the point at which the press-off occurred, the needle bar is returned to knitting position and the originally pressed-off blank completed with the remainder of the blanks of the new set. In order to apply draw-off tension to the pressed-off blank after it is topped onto the needles, the blank is usually tied to the reel which causes the blank to be wrapped around the reel as it rotates in the draw-off direction. With the present reel structure, however, the center section would remain stationary and no tension applied to the blank attached thereto.

Under these circumstances, it is essential that the center reel section 39 rotate with the end sections 37 and 38 of the reel, and the shaft 34. For this purpose, means is shown in Figs. 5, 6, 7 and 8, for locking the center section 39 to the end section 38 of the reel unit 36. The lock means shown comprises a pin 56 slidable in the bearing members 42 and 43 for the section 38 and engageable in one of a series of apertures 57 in the bearing member 50, as shown in Fig. 8, for the center section 39, adjacent to the bearing member 43 for the section 38. To lock the center section 39 to the end section 38 and therefore the shaft 34, the pin 56 is pressed into one of the apertures 57.

When the set of blanks, including the originally pressed-off blank, is completed and removed from the machine, it is desirable that the center section 39 be released from the end section 38 by removing pin 56 from the aperture 57 to permit the center section 39 to again freely rotate on the shaft 34. For this purpose a second pin 60 is provided also slidable in the bearing member 42 of the section 38. The pin 60 is connected to the pin 56 by a lever 61, one end of which is engaged in a slot 62 in the pin 56 and the other end of which is engaged in a slot 65 in the pin 60. The lever 61 is pivoted on a shouldered screw 66 carried in an aperture 67 in the bearing member 42 of the end section 38 of the reel unit 36. In order to remove the pin 56 from the aperture 57 the pin 60 is pressed to the left from the position shown in Fig. 7 to that shown in Fig. 5 thereby, turning the lever 61 in a counterclockwise direction to move the pin 56 to the right and out

of the aperture 57. The pins 56 and 60 are held in either the position of Fig. 5 or Fig. 7 by means of a spring washer 70 positioned between the head of screw 66 and the lever 61.

As previously stated, the machine is stopped at a time when the last course at the toe end of each blank has been completed. This can be done, if desired, while said last course is on the needles although the blank is shown in Fig. 1 as it appears after it has been pressed off. The tension is then taken off the shaft 34 either automatically or manually depending upon the type of machine used and the shaft 34 turned by hand to bring the welt wires directly above the shaft 34 so that they can be slipped out of the hooks and welts with a maximum of convenience. Before or after the next set of blanks have been hooked up, the blanks are removed from the sections 39 of reel unit 36, the sections freely rotating to facilitate such removal.

It will clearly appear from the foregoing that the objects primarily stated may be satisfied with the illustrated form of the invention; and that there is provided a simple and efficient means by which blanks, such as stockings, after completion of knitting upon a full-fashioned knitting machine, may be readily removed from the fabric take-up reel with the minimum chance of damage through strain incident to the pulling or unwinding of such finished blanks from the reels. Moreover, the invention provides, and as is hereinbefore described in detail in one form, for the fixed coupling of the normally rotatable center section of the reel to its mounting shaft, thus permitting the use of this center section in any manner when required to be positively driven.

Of course, the improvements specifically shown and described, by which the above described results are obtained, can be changed and modified in various ways without departing from the inventions herein disclosed and hereinafter claimed.

We claim:

1. A cylindrical fabric draw-off reel unit for a flat knitting machine comprising a shaft, two end sections fixed to said shaft and having draw-off straps connected thereto, and a central section on said shaft and having bearing means between itself and the shaft adapting the central section for free rotation relative to the shaft, said central section having an uninterrupted smooth cylindrical surface.

2. A fabric draw-off reel unit for a flat knitting machine and having a shaft, three sections on said shaft the two outer sections of which are fixed to the shaft and the central section of which is normally free to revolve relative to the shaft, and means operating between said center and outer sections to selectively fix said central section to move with said outer section.

3. A cylindrical fabric draw-off reel unit of substantially uniform diameter for a flat knitting machine and having a shaft, two end sections fixed to said shaft, draw-off straps connected to said end sections, and a central section between said end sections mounted on said shaft for free rotation relative to the shaft, and a latch mounted on one of said end sections and including a part fixedly engaging said central section when the latch is in use.

4. A cylindrical fabric draw-off reel unit of substantially uniform diameter for a flat knitting machine and having a shaft, two end sections fixed to said shaft, draw-off straps connected to said end sections, and a central section on said

shaft between said end sections mounted on said shaft for free rotation relative to the shaft, and means mounted on one of said end sections movable to engage with said center section to lock the latter to said end sections.

5. A cylindrical fabric draw-off reel unit of substantially uniform diameter for a flat knitting machine and having a shaft, two end sections fixed to said shaft and having draw-off straps connected thereto, a central section on said shaft between said sections and having bearing means between itself and said shaft adapting the central section for free rotation relative to the shaft, said central section having an uninterrupted smooth cylindrical surface, and means for locking said center and end sections together.

6. A cylindrical fabric draw-off reel unit of substantially uniform diameter for a flat knitting machine and having a shaft, two end sections fixed to said shaft and having draw-off straps connected thereto, a central section on said shaft between said sections for free rotation relative to the shaft, said central section having an uninterrupted smooth cylindrical surface, and a latch mounted on one of said end sections and including a part fixedly engaging said central section when the latch is in use.

7. A cylindrical fabric draw-off reel unit for a flat knitting machine and having a shaft, two end sections each having two transverse members fixed to said shaft, both of the transverse members of one of the end sections being apertured in a line parallel to said shaft, the end sections having draw-off straps connected thereto, a central section on said shaft between said end sections and having two transverse members in rotative contact with said shaft, one of said transverse members of said central section having apertures for alinement with said apertures in said end member, and said central section having an uninterrupted smooth cylindrical surface, and a latch mounted on one of said end sections and comprising a pin mounted parallel to the shaft in the apertures in the transverse members of said one of said end sections and having latching engagement in use in an aperture in said one of the transverse members of the central section.

8. Fabric draw-off means for a flat knitting machine comprising, a draw-off shaft, a draw-off reel unit carried thereon including end sections fixed to said shaft, a center section carried on said shaft and normally free to revolve relative to the shaft and said end sections, and means for latching the center section in fixed relation to the end sections of said reel unit.

9. A fabric draw-off reel unit for a flat knitting machine comprising a shaft, a pair of end sections fixed to said shaft, means for connecting draw-off straps to said end sections, and a center section rotatable relative to said shaft between said end sections and having an uninterrupted surface.

10. A fabric draw-off reel unit for a flat knitting machine comprising a shaft, a pair of end sections fixed to said shaft, means for connecting draw-off straps to said end sections, a center section mounted on said shaft between said end sections and movable relative thereto and having an uninterrupted surface, and a latch adapted to connect the center section to an end section when desired.

11. A fabric draw-off reel unit for a flat knitting machine comprising a shaft, a pair of end sections fixed to said shaft and having means facilitating the connection of draw-off straps thereto,

5 10 15 20 25 30 35 40 45 50 55 60 65 70 75

a center section supported on and rotatable relative to said shaft, and latch means adapted to connect the center section to an end section when desired and constructed and arranged so that a portion projects from the outline of the unit when the center section is free and so that another portion projects when the center section is latched.

12. A fabric draw-off reel unit for a flat knitting machine comprising a shaft, a pair of end sections fixed to said shaft and having means facilitating the connection of draw-off straps thereto, a center section rotatably mounted on said shaft, and a latch means adapted to connect said center section with an end section and biased to stand either in position to connect the center to the end section or in position to free the two.

13. A fabric draw-off reel unit for a flat knitting machine comprising a shaft, a pair of end sections fixed to said shaft and having means facilitating the connection of draw-off straps thereto, a center section supported on and rotatable relative to said shaft, and means adapted to furnish a driving connection in the draw-off direction between the center section and an end section.

14. A fabric draw-off reel unit for a flat knitting machine comprising a shaft, a pair of end sections fixed to said shaft and having means facilitating the connection of draw-off straps thereto, a center section supported on and rotatable relative to said shaft, and a latch means adapted to connect said center section with an end section when desired and including a spring biasing the latch means to remain stationary either when in position to connect the center with the end section or when in position to free the two.

15. A fabric draw-off reel unit for a flat knitting machine comprising a shaft, a pair of end sections fixed to said shaft and having means facilitating the connection of draw-off straps thereto, a center section rotatably mounted on said shaft, and latch means adapted to connect said center section with an end section and including a pair of pins substantially parallel to the shaft, one of which provides the latching action, and a spring releasably holding said pins to either latch the center section or free it.

16. A cylindrical fabric draw-off reel unit for a flat knitting machine comprising a shaft, two end sections fixed to said shaft and having draw-off straps connected thereto and a central section on said shaft and rotatable relative thereto, said end sections abutting said central section to substantially prevent end play thereof.

17. A method of operating a flat knitting machine having a draw-off reel including a shaft, end sections fixed to said shaft and a central section rotatable on said shaft comprising the steps of drawing off fabric during knitting and winding the fabric on said central section by tension applied to a welt wire engaged with the fabric, removing said wire from the fabric, and revolving said central section by tension applied to an end of the fabric to release the fabric from the central section and thereby remove it from the machine.

18. A fabric draw-off reel for a flat knitting machine comprising a shaft, end sections fixed to the shaft, means on said end sections for the attachment of draw-off straps thereto, and a central fabric reel section between said end sections and in substantially abutting relationship thereto to define joints therebetween, said cen-

tral section being mounted for rotation relative to said shaft and including a cylindrical shell extended to overlie said joints.

19. A method of operating a flat knitting machine having fabric draw-off means including a shaft, end sections fixed to the shaft for rotation thereof and to which are attached draw-off straps releasably secured to a welt wire engaged with the fabric being knitted, and a central fabric reel section rotatable relatively to said shaft, comprising the steps of drawing off fabric during knitting and winding the fabric on said central reel section by rotating said shaft, and, after knitting is completed, removing the welt wire from the fabric and revolving said central section by applying tension to the fabric to unwind the fabric from the central section and thereby remove it from the machine.

20. Fabric draw-off means for a flat knitting machine comprising a draw-off shaft, a draw-

off reel carried thereon and including end sections fixed to said shaft, a central reel section carried on said shaft and normally free to revolve on the shaft, and means mounted on one of said sections and free of direct connection to the fabric for securing the central section in fixed relationship to an end section of the reel for rotation therewith.
